UNITED STATES PATENT OFFICE.

ROBERTO ALMAGRO, OF HABANA, CUBA.

BAGASSE AND LIQUID-FUEL FURNACE.

Application filed June 29, 1922. Serial No. 571,586.

To all whom it may concern:

Be it known that I, ROBERTO ALMAGRO, a citizen of the Republic of Cuba, residing at Habana, Republic of Cuba, have invented certain new and useful Improvements in a Bagasse and Liquid-Fuel Furnace, of which invention the following is a complete specification.

This invention relates to furnaces which burn bagasse and a liquid fuel such as petroleum in different fire-places and has for its principal object to provide a furnace of such construction that there are included in the same several improvements which allow the most thorough cleaning of the furnace, greater and more uniform heating of the boilers and prove favorable to the preservation of the same.

An object of the invention is the disposition of the fire-places in respect to the principal body of the furnace within which are mounted the boilers in such a manner that the boilers are not in direct contact with the flames and burning gases of the fire places, but are separated from same, only receiving in an indirect manner the heat of the burning gases.

A further object of the invention is to provide a transverse tunnel to the furnace, formed underneath the fire bridges, which tunnel is provided with damper doors which permit the cleaning of the front part of the furnace and damper doors which permit the cleaning of the rear part of the furnace.

A further object of the invention is to provide in the construction of the furnace such a disposition as will permit that the gases from burning, proceeding from the fire places wherein bagasse is burned, are lead and distributed at their outlet from said fire place towards ash pits located behind the fire place for burning liquid fuel and from thence continue their circulation over the fire bridges towards the rear part of the furnace.

A further object of the invention is a disposition in the rear wall or back of the furnace which facilitates the better gathering of the residues of the combustion.

Another object of the invention is the inclined disposition of the rear wall of the fire place for burning bagasse with a view to facilitating the leading of the gases of combustion towards the outside of the fire place.

More advantages and other considerations

are deduced during the course of this description and with the help of the attached drawings in which the same reference characters designate the same parts.

In the attached drawings:

Figure 1 is a fragmentary front elevation of the furnace.

Figure 2 is a vertical longitudinal section according to the line 2—2 of Figure 1.

Figure 3 is another vertical longitudinal section according to the line 3—3 of Figure 1.

Figure 4 is a horizontal section according to the line 4—4 of Figure 2.

In these figures there is represented a furnace A of a cubical shape within which two boilers 1 and 2 are mounted and which is provided at its front part with three fire places; a central fire place 3 for burning

bagasse and two fire places 4 and 5 for burning petroleum on opposite sides of the first and the three in an advanced position with relation to the body of the furnace A which contains the boilers. The fire place

for burning bagasse as is usual has its hopper 31 for feeding bagasse, grates 6, ash pit 7, damper door 8' to fire place, damper door

8 for the ash pit and, above the damper door 8' an aperture 9 with its door for feeding wood to the fire place 3. The rear wall 10 of the fire place is inclined as is seen in Fig.

2 in order to facilitate the leading of the burning gases towards the outside of the fire place.

The fire places 4 and 5 for burning petroleum are also provided with their liquid fuel burners 11 and 12, ventilation holes 13 and 14 and dampers 15 and 16.

As is shown by Figures 2 and 3, the fire places 3, 4 and 5 slightly extend inwards of the body of the furnace constituting the rear part of the casings of fire places 4 and 5 rests for the front part of the boilers 1 and 2 these therefore remaining free of direct contact with the fire places. Behind

the fire places 4 and 5 there are ash pits 4' and 5' to which gases proceeding from the fire place 3 for burning bagasse have access through passways 27' formed between the

lateral walls of fire place 3 and an extension 27 of partition 26' which separates boilers 1 and 2; the extension 27 separates ash-pits 4' and 5'. A small vault 3''' covers the space which exists behind fire place 3,

being a continuation of cover 3'' of said fire place and extending up to the projection

27; therefore the burning gases proceeding from fire place 3 and gathered up under the small vault 3''' are distributed and forced towards ash-pits 4' and 5' thru passways 27' as is shown by arrows in Figure 4, the bevelled outline of the end or head of projection 27 facilitating this circulation, this circulation continuing over the fire bridges 22 underneath which there is formed a tunnel 23 transverse to the furnace, the ends of which open to both sides of same, said tunnel being provided on one side with doors 24 for inspection and cleaning of the ash-pits behind fire places 3, 4 and 5 and on the other side with doors 25 for inspection and cleaning of the rear smoke passages underneath boilers 1 and 2 to which access is also had through the doors 21, the floor of said passages being inclined or sloping as is shown by 26' to facilitate the better collection of the residues or waste of burning.

Lastly, as is shown by 28, I provide, back of the boilers "1" and "2", a continuous vault, which forms a buffer plate, preventing the burning gases from circulating upwards, but forcing them towards the front of the furnace through the fire flues of boilers 1 and 2.

Of course, there can be introduced some changes in the details of the structure which constitute improvements, therefore I do not limit myself to what has been previously set forth but I desire that Letters Patents should cover the following claims:

1. In bagasse and liquid fuel furnaces, a furnace body which contains a battery of steam boilers, having in front a chamber for burning bagasse, and chambers for burning liquid fuel on each side of the chamber for burning bagasse, said chambers being in an advanced position with regard to the furnace body which contains the boilers, the front ends of these extending slightly over the chambers, and a tunnel situated across the fire bridges of the chambers, the outlets of said tunnel ending at opposite sides of the furnace with damper doors, and to which tunnel the burning gases incoming from the chambers do not have any access.

2. In bagasse and liquid fuel furnaces, a furnace body inclosing a battery of steam

boilers having in front a chamber for burning bagasse and a chamber for burning liquid fuel on each side of the chamber for burning bagasse, the three said chambers being in an advanced relation with regard to the principal body of the furnace which contains the boilers, the front ends of same extending over the chambers; ash pits placed back of each chamber and a cleaning tunnel across the furnace below the altars of these chambers, the ends of said tunnel having outlets on each side of the furnace, and said tunnel being provided with damper doors which permit access towards the ash pits back of the chamber and towards the lower flues of the boilers, said doors preventing access of the burning gases from the chambers towards the interior of said tunnel.

3. In bagasse and liquid fuel furnaces, a furnace body inclosing two steam boilers having in the front part of the furnace a bagasse burning chamber, the rear wall of which is sloped inwardly, and a liquid fuel burning chamber on each side of the bagasse burning chamber, these three chambers being in an advanced relation with regard to the furnace body which incloses the steam boilers, the front ends of the steam boilers extending over the chambers and being supported by the covering thereon, a partition wall situated between the steam boilers separating them and extending towards the rear wall of the bagasse burning chamber, the front end of said partition wall ending in guiding surfaces to lead the gases incoming from the chambers; passways formed between the partition wall and the side walls of the bagasse burning chamber to admit the gases incoming from said bagasse chamber in two equal and independent volumes separately toward the rear flues; a vault situated back of the rear flues of the boilers and a cleaning tunnel situated across the fire bridge of the chambers transverse to the furnace and which opens on both sides of the furnace, said tunnel having damper doors on both sides affording access to the front and to the rear of the furnace.

In witness whereof I affix my signature.

ROBERTO ALMAGRO.
